UNITED STATES PATENT OFFICE.

WALTER V. TURNER, OF WILKINSBURG, PENNSYLVANIA, ASSIGNOR TO THE WESTINGHOUSE AIR BRAKE COMPANY, OF WILMERDING, PENNSYLVANIA, A CORPORATION OF PENNSYLVANIA.

MOTOR FOR DOOR AND STEP CONTROLLERS.

1,277,000.

Specification of Letters Patent. Patented Aug. 27, 1918.

Application filed May 14, 1917. Serial No. 168,338.

To all whom it may concern:

Be it known that I, WALTER V. TURNER, a citizen of the United States, residing at Wilkinsburg, in the county of Allegheny 5 and State of Pennsylvania, have invented new and useful Improvements in Motors for Door and Step Controllers, of which the following is a specification.

This invention relates to motor devices 10 more particularly adapted for controlling the doors and steps of railway vehicles.

For operating doors and steps, it has heretofore been proposed to employ a pneumatically controlled piston device, and in order 15 to insure quiet and smooth final movement of the doors, the fluid pressure on the piston device is so regulated that the same acts as a cushion to prevent the too rapid final movement of the piston device and consequently the doors.

The principal object of my invention is to provide a spring device for cushioning the action of the motor piston device.

In the accompanying drawing; Figure 1 25 is a central vertical section of a door and step controlling device embodying my invention; Fig. 2 an inverted plan view thereof; Fig. 3 a side elevation thereof, partly in section; and Fig. 4 a transverse section 30 thereof on the line *a—a* of Fig. 2.

As shown in the drawing, the construction may comprise a cylinder casing 1 having piston chambers 2 and 3 containing the respective pistons 4 and 5 connected by a piston rod 6.

The rod 6 is provided with rack teeth 7 adapted to mesh with the teeth of a gear segment 8 secured to a shaft 9 which is operatively connected to the car doors and steps 40 for operating same.

For supplying and releasing fluid under pressure to and from the piston chambers 2 and 3, pipes 10 and 11 are provided.

According to my invention, there is secured to the cylinder casing 1, a spring casting 12 containing oppositely arranged movable abutments 13 and 14 between which is interposed a coil spring 15.

The abutment 13 is provided with a longitudinally extending lug 16, apertured at its outer end for a pin 17 and extending through an aperture in the abutment 14 is a screw threaded rod 18 having a nut 19 for

engaging the outer face of the abutment and adapted to be screwed into a member 20 55 which is apertured to receive a pin 21. The rod 18 is slidably mounted in a cylindrical extension 23 of the abutment 13 and is slotted for a guide pin 22 secured to the inner end of the extension, so as to prevent rotation of the rod 18.

Mounted on the opposite ends of the pins 17 and 21 at opposite sides of the spring casing are links 24 and each link is provided with a centrally arranged slot 25 within 65 which a cam lever 26 works.

The cam levers 26 are secured to opposite ends of the shaft 9.

The pins 17 and 21 work in slots 27 in the links 24 so as to permit relative movement of the pins in one direction with respect to the links.

In operation, when the doors are to be opened, fluid under pressure is supplied to one of the pistons, say piston 4, while the other piston is connected to the atmosphere. The piston device is then shifted to the right, causing the rack 7 to rotate the gear segment 8 and shaft 9 so as to effect the opening of the car doors and steps. Upon 80 a predetermined movement of the parts, the cams 26 will engage the links 24 at the ends of the slots 25 and move the links toward the left, so that the pin 21 acts to force the abutment 14 inwardly and thus compress 85 the spring 15, the opposite ends of the links 24 being free to move relatively to the pin 17 by reason of the slots 27.

It will thus be seen that the final movement of the piston device is resisted by the 90 spring 15 so that a cushioning of the movement of the piston device is produced with a corresponding retardation and cushioning of the doors and steps.

In a similar manner, when the doors and steps are to be closed, fluid under pressure is supplied to piston chamber 3 while piston chamber 2 is connected to the exhaust and the piston device is shifted to the left, causing the rotation of the cam 26 to the right 100 and the inward movement of abutment 13 to compress the spring 15.

Having now described my invention, what I claim as new and desire to secure by Letters Patent, is:—

1. In a car door and step controlling de-

vice, the combination with a piston device operated by fluid under pressure, of a spring, a cam lever operated by said piston device, movable abutments engaging opposite ends 5 of the spring, and means adapted to be engaged by the cam lever for operating one of the abutments according to the direction of movement of said piston device.

2. In a car door and step controlling device, the combination with a piston device 10 operated by fluid under pressure, of a spring, a cam lever operated by said piston device, movable abutments engaging opposite ends of the spring, and links operatively con-

nected to said abutments and adapted to be 15 operated by said cam lever.

3. In a car door and step controlling device, the combination with a piston device operated by fluid under pressure, of a spring, movable abutments engaging opposite ends 20 of the spring, links operatively connected to said abutments, and means operated by said piston device for engaging and actuating said links upon a predetermined travel of the piston device in either direction. 25

In testimony whereof I have hereunto set my hand.

WALTER V. TURNER.
